UNITED STATES PATENT OFFICE

ENRICO OLMO, OF MILAN, ITALY, ASSIGNOR TO GUIDO SANTAGOSTINO, OF MILAN,
ITALYDEVICE FOR AUTOMATIC MOORING AND DEPTH-TAKING UNDER WATER OF BUOYS,
MINES, AND OTHER APPARATUS

Application filed April 2, 1932, Serial No. 602,693, and in Italy April 27, 1931.

The present invention relates to improvements in devices for the automatic mooring and depth-taking under water level of buoys, mines and other apparatus.

5 The main object of my invention is to provide an apparatus of the character indicated which is unusually practical, shock proof and safe, and also has a large capacity for sounding cable by virtue of a stationary bobbin, and is further provided with efficient means for controlling and braking the cable during sounding and depth-taking, with the result that the apparatus is convenient, safe and compact as a whole.

10 Other objects and the various advantageous features inherent in the novel structure and arrangement of my invention will appear more fully in detail as this specification proceeds.

15 The accompanying drawings illustrate, merely by way of example, an execution form of the invention.

Fig. 1 is a vertical axial section.

Fig. 2 is a detail plan view.

20 The apparatus works on the plummet system of many self-anchoring mines and buoys already in use. The same comprises four main parts, which are:

25 The body —*t*— consisting in a tight casing having a strong positive upward thrust or buoyancy when immersed and which, when used as a mine is provided with explosive charges, detonators and firing gears and with all other parts, forming the equipment of a mine. In the following, we shall call the body —*t*— by the term of "mine."

30 The anchor or sinker —*a*— is intended to stabilize itself at the sea bottom.

35 The rope —*f*— constitutes the means by which the anchor retains the mine.

The plummet —*s*— is connected to the anchor and preceding it by the free length of its attaching rope —*fs*— in its travel towards the bottom.

40 At the moment of launching, the said four parts form a single combination.

45 Shortly after the launching, the plummet commences its descent to the bottom as first; then the sinker follows it at a predetermined distance, the sinker being connected to the

plummet by means of the rope —*fs*— the length of which is adjustable. The anchor contains a drum from which, according as the anchor sinks, the main rope —*f*— for connection with the mine —*t*— (which remains afloat) unwinds itself. When the plummet touches the bottom, it stops the unwinding of the rope —*f*—, so that the anchor as it continues to sink till it comes into contact with the ground—drags the mine below the water surface through a distance corresponding to the length by which the plummet precedes the sinker in its descent to the bottom. In the mines heretofore constructed the drum contained in the anchor and on which the rope is wound must revolve about its axis in order to allow of the rope to unwind itself according as the anchor sinks. In the present invention, on the contrary, a device is mounted 55 on the anchor, which permits of using a rope drum which is stationary relatively to the anchor. More precisely, the bobbin —*b*— supplied with the rope, and having a vertical axis, is mounted on the sinker bottom. 60 Above the upper head of the drum, a cross bar —*tr*— is arranged, which can revolve about the axis of the said drum and carries a sheave —*ca*— 65 at one of its ends.

This sheave has its groove very deep and 70 flared, and has its axis suitably inclined to the vertical. The outer end of the rope mounted on the bobbin is passed over the sheave —*ca*— and then over a second sheave —*cr*— arranged in the center portion of the cross bar 75 so as to convey the rope upwardly and be attached to the mine —*t*—.

80 During the anchor-sinking operations, the mine —*t*— which has remained afloat exerts a certain tensioning action on the whole 85 length of rope —*f*— between its attachment to the mine and the bobbin on which the rope is wound. The tension exerted on this rope is transmitted by the sheave —*ca*— to the cross bar —*tr*— and due to said tension-force the component, tangential to the circumference which the sheave —*ca*— can describe around the bobbin, causes the cross bar —*tr*—, as long as the latter is free, to revolve, thus allowing the bobbin to let out rope wound thereon in the 90 95 100

amount required to permit the sinking of the anchor.

The starting of the unwinding of the rope can be prevented, and the unwinding can be stopped as well as at any desired moment, in two ways: First, by gripping with a suitable brake attached at the anchor body, the rope —*f*— as it is being let out. The second manner of stopping the unwinding of the rope, 10 which is the method illustrated in the accompanying drawings, consists in locking the cross bar *tr* carrying the sheave *ca*. This can easily be performed by means of a claw clutch, or a friction clutch, or a combination 15 of a friction clutch and a claw clutch acting at suitable points of the cross bar. The friction or claw clutch may act on the rotation centre as indicated on the drawing, or it may act at the two ends of the cross bar and clamp 20 the bar by means of suitable friction slides or claws against the anchor rim in front of which the cross bar revolves. The brake and stop device may be caused to act on a centered rim fitted on the cross bar as a separately 25 manufactured piece, braking means and systems being used for instance similar to those employed for acting on the drum of the brakes usually mounted on automobile wheels and in other like cases. The said braking 30 and stopping device is controlled by the plummet by means of suitable devices. One of the arrangements that may be adopted is illustrated by way of example in the accompanying figures. The plummet rests on the cover 35 *co* until after the launch of the complex and till the moment when the plummet must start working, which cover closes the opening in which the plummet is lodged, so that its weight cannot tension the rope which, leading 40 from the plummet passes over the tackle *bo* and extends to a suitable point of attachment on the anchor body. The overlying spring —*m*— acting on the body of the clutch —*i*— (which latter, below, is connected to 45 the tackle by a bolt) as long as the rope, passing over the tackle *bo*, is not weighted by the plummet, is adapted to bring the clutch —*i*— into engagement with the piece —*p*— of the cross bar. This prevents the rotation 50 of the cross bar which normally entrains into its rotation the device —*i*—, whereas the latter cannot rotate when blocked by a small bar *sb* the ends of which abut against the sides of grooves formed in the cylinder —*c*— 55 for the purpose of accommodating the ends of the bar *sb*. When the plummet, the shape of which is suitably designed so as to have a proper water-penetration power, after leaving its lodging remains hanging on the sink- 60 er, and the rope *fs* thus acting on the tackle overcomes the resistance of the spring —*m*—, lowers the member of the clutch —*i*— and allows the rotation of the cross bar and consequently the unwinding of the rope and the 65 sinking of the anchor. As soon as the plummet

touches the bottom, all traction effect on the rope *fs* ceases, and the spring —*m*— as no opposing force being now opposed to it, will again bring the clutch —*i*— into engagement with the cross bar; in this manner the cross 70 bar will be locked and the unwinding of the rope stopped. The mine will now sink to the depth required to allow the sinker —*a*— to rest on the ground, thus completing the operation of mooring the mine —*t*— at the desired depth under the water surface. In order to ensure the proper working of the combination, it is necessary to make provisions against all possibilities of the plummet 75 issuing from its lodging prematurely. To this effect the retaining cover is hinged and held in place by a safety lock which is not removed till the moment when the launching is to be performed. After launching, the opening of the retaining cover is brought about by the plummet weighing on the cover, but only after a suitable delay, because the cover *co*, in order to open itself, must overcome the resistance of one of the usual glycerine dashpots. 80

After the cover has been opened, the plummet will freely slip into the water and immediately sink the free length of the rope *fs* retaining the plummet. This free length is adjustable in order to obtain the depth-taking 95 of the body —*t*— at various depths under the water surface. To this effect, as shown on the drawings, the rope *fs* is passed over a series of fixed retaining pegs *rf* and over a series of movable retaining pegs *rm*. By extracting, from outside the anchor and prior to the launching, the first of the pegs *rm* two rope lengths leading further pegs *rm*, an ever increasing length of the rope *fs* will be released. 100

Should a better regulation be desired than is thus obtainable, the end of the rope *fs* may be wound on a drum *ts*: for example, by manipulation of suitable holding means, from outside the anchor casing, the unwinding of a greater or smaller length of the rope *fs* from the said drum will be rendered possible, in addition to the amount of free rope *fs* obtained from the manipulation of the abovementioned movable pegs. In order to ensure the connection of the body —*t*— to the anchor *a* up to the moment when the anchor is about to sink, so as to ensure also the tightness of the joints interposed between the body —*t*— and the upper edge of the anchor and thus while the flooding of the anchor is prevented, make certain that the combination shall possess a buoyancy sufficient to keep it floating. For this purpose, it will suffice to keep the end of the rope —*f*— attached to the body —*t*— by means of a screw spindle and screw nut —*d*—. The nut —*d*— or the spindle can be tightened by means of a suitable wrench across a slot formed in the side of the anchor casing. The 110 115 120 125 130

locking of the cross bar *tr* prevents the unwinding of the rope, and if the rope end secured to the mine has been made taut by means of the nut —*d*—, the mine —*t*— will

5 remain firmly connected to the anchor —*a*—. For the connection of the mine —*t*— to the anchor —*a*— it is also practicable to adopt other special contrivances adapted to be automatically disconnected as soon as the plumb-

10 met has drawn the rope *fs* taut.

The device accordingly adapted to the present invention by the unwinding of the rope —*f*— imparts to the rope a twist turn for each rope turn unwinding from the bobbin; 15 this twisting, according to the revolving direction of the cross bar and according to the twist of rope strands, can either add itself to or subtract itself from the rope's own twist, the tendency of the rope to untwist being 20 thus increased or diminished.

Taking into due account this tendency as well as the auxiliary twists caused by unwinding, suitable blades *pa* are provided, according to the invention, on the outer surface 25 of the anchor casing, the blades being generally arranged like the blades of a propeller in order to impart to the anchor body, during its sinking, such a rotating movement as will neutralize the untwisting tendency of 30 the rope itself. The cross bar *tr*, in its revolving motion in the water, encounters a certain amount of resistance. According to the present invention, this resistance can be suitably adjusted by giving to the cross bar a suitable 35 shape, generally similar to that of a propeller, in order to obtain a useful even braking action.

Having now particularly described and ascertained the nature of my said invention 40 and in what manner the same is to be performed, I declare that what I claim is:—

1. Device for automatically mooring subaqueous buoys and mines, including the combination, with a hollow anchor, of a removable bobbin adapted to be placed in a fixed position within said hollow anchor, with its axis vertically disposed therein, and provided with a mooring cable which is wound upon said bobbin, a cross bar provided with return 45 sheaves for said cable rotatable above said bobbin about the vertical axis of the same in order to unwind said cable from said bobbin while the latter remains stationary with respect to said anchor, a braking device in said anchor adapted to check rotation of said crossbar and the unwinding of said cable, and a plummet in said anchor associated with said braking device suspended on a plummet line and adapted to be let out a limited distance from the anchor and simultaneously prevent said braking device from checking rotation of said crossbar while pendently hanging from the plummet line, and adapted to slack the plummet line upon 55 contact of the plummet with the bottom and

thereby allow the braking device to freely operate to check rotation of said crossbar and prevent further paying out of the mooring cable for said stationary bobbin.

2. Device according to claim 1 wherein the hollow anchor primarily consists of a casing provided with exterior ribs serving as the blades of a screw adapted to impart rotation to the anchor as a whole in order to twist or untwist the mooring cable as desired, 70 while it is being unwound from the bobbin within the anchor.

3. Device according to claim 1 wherein the crossbar has a balanced and symmetrical form in order to rotate smoothly and avoid 80 vibration of the anchor.

4. Device according to claim 1 wherein the crossbar is provided with blades adapted to provide a braking effect on the rotation of the crossbar on the water. 85

5. Device according to claim 1 wherein the braking device in the anchor is shiftable from one position in which it blocks rotation of the crossbar, by the effect of the weight of the plummet, to another position in which it releases said crossbar for free rotation thereof, the contact of the plummet with the ocean floor removing the effect of its weight upon the braking device, whereupon the latter is adapted to automatically return to the position in which it blocks rotation of the crossbar. 90

6. Device according to claim 1 wherein the braking device is normally retained by a spring in raised position wherein it engages a portion of said crossbar and blocks rotation of the latter while free from the effect of the weight of the plummet, and when the plummet is being let down from the anchor, the weight of the same effects neutralization of said spring with a limited lowering of said braking device into a disengaged position in which the crossbar is released and free to rotate and unwind cable from the bobbin in 100 said anchor. 110

Signed at Milan (Italy), this 18th day of March 1932.
